DESIGN FOR A TAX FORM DEVICE

Joseph W. Honeycutt, Kannapolis, N. C.

Application April 19, 1945, Serial No. 119,085

Term of patent 7 years

(Cl. D64—11)

To all whom it may concern:

Be it known that I, Joseph W. Honeycutt, a citizen of the United States, residing in Kannapolis, county of Cabarrus, and State of North Carolina, have invented a new, original, and ornamental Design for a Tax Form Device, of which the following is a specification, reference being had to the accompanying drawing, forming part thereof.

Fig. 1 is a plan view of a tax form device showing my new design;

Fig. 2 is a longitudinal sectional view on line 2—2 of Fig. 1;

Fig. 3 is a top end view; and,
Fig. 4 is a bottom end view.

I claim:

The ornamental design for a tax form device, substantially as shown.

JOSEPH W. HONEYCUTT.
